DUDLEY HOWARD WIGGINS, OF INDIANAPOLIS, INDIANA.

MICROPHONE FOR TELEPHONIC INSTRUMENTS.

Application filed October 30, 1922. Serial No. 597,834.

One object of this invention is to improve transmitters for telephones of the microphone type and the like by making the same extremely sensitive and capable of transmitting minor tones or overtones, as well as major or fundamental tones, whereby the tones of the human voice and other tones will be more accurately, fully and naturally reproduced. It is well known that the ordinary microphones for telephones or the like are so made that they fail to transmit or reproduce the minor tones and at the same time they relatively emphasize and magnify the major tones, so that there is relatively much noise and the minor tones are largely lost, and the timbre of the human voice or full quality of the tones is not reproduced. With this invention the minor tones are reproduced and the major tones not relatively exaggerated, but the human voice or other tones are received and transmitted so as to be perfectly natural and with all the original timbre and quality of tone. This is true not only of tones from the human voice, but musical tones where the minor tones and those which give richness and quality to the music are largely lost in ordinary microphones.

Another object of the invention is to enable one to talk into the microphone of a telephonic instrument without yelling or talking close to the microphone. With this invention the tone will be full and clearly reproduced when the person talking through it is anywhere in the room. Mouthpieces are unnecessary and one is not required to hold the instrument. The tones will be transmitted when one is twenty feet away and with his back to the microphone.

Another object of this invention is to provide a microphone for telephones and the like that can be enlarged to any size that may be required or desired for any use in any situation. In this invention the diaphragm construction is not limited to any particular size, as the diaphragm is not vibrated as a unit so that while the transmitter may be three inches in diameter on the ordinary telephone, with this invention it may be three feet in diameter, or greater, for receiving proceedings of conventions or large gatherings or orchestral music, or

other complex and delicate sounds for radio broadcasting or any other purpose.

One feature of this invention consists in using a sheet of metal foil, preferably gold foil, as the diaphragm member, and which is not rigid or relatively stiff or resilient like the ordinary diaphragm, which must be vibrated as a unit, whether mounted at its margin tightly or loosely. The diaphragm in this invention is very thin and pliable and substantially non-resilient and arranged in connection with other parts of the transmitter so that it forms a considerable number of small similar sections, each of which is in the nature of a diaphragm acting by itself and without physically changing or affecting any other section or part of the total foil diaphragm member, although all the sectional diaphragms act synchronously and cumulatively to produce the full complement of tones and the sectional diaphragms engage the same mass of carbon granules, minor as well as major tones. The ordinary transmitter diaphragm must be wholly or partially vibrated which can only be done by powerful sound waves. This is because of the size and inertia of the diaphragm and consequently it is not much affected by the minor tones and is not at all affected by those tones which produce sound waves too weak to move the diaphragm. This kind of diaphragm also injures and confuses the reproduced tones because of the lag, due to the time required by the sound waves to move the entire diaphragm or overcome its inertia. The result is that the minor tones will not be synchronous with the overtones in the reproduction. In this invention the individual or sectional diaphragm is so small and so thin and pliable that it is sensitive to slight sound waves, as the inertia is negligible, whereby the waves from the minor tones can move it sufficiently to be reproduced and without lag.

Another feature of this diaphragm construction is that it can be enlarged to any extent without injuring its function, as the entire diaphragm member is not vibrated as a whole, but is sectionalized into many small diaphragm sections which act independently of each other, but synchronously. It is obvious, therefore, that the increase

in size or number of sections or size as a whole will not reduce the sensitiveness or efficacy of the transmitter, but will have the opposite effect of making it a more powerful and sensitive transmitter because there is acting in unison many diaphragm sections.

Another feature of the invention consists in the means of mounting said metal foil diaphragm so that it will perform its function as desired. This is accomplished by associating it with a back non-conducting reticulated frame adjacent the granular carbon. The foil is held tightly against this frame so that the portions of the foil in direct contact with the frame do not vibrate, but only the intermediate surfaces of the foil vibrate and act as sectional or separate diaphragms. In addition, a similar reticulated frame, preferably a conductor, is placed in front of the foil so that the foil is practically clamped or held between these two frames which makes an easily made mounting of the foil and one which causes it to operate successfully.

Another feature of the invention is in adding, to the foregoing, means in the nature of a layer of wood-like material in front of the foil or said front frame. Steel wool or other metallic wool in mass form is preferable for this purpose but any other kind or resilient material having substantially the same irregular curly formation as the steel wool may be employed so long as it can be readily penetrated by the sound waves and yet not be responsive to them. This steel wool is held against the front electrode frame preferably by another wire screen in the front of the steel wool, so that the layer of fibrous material will be compressed into a flat mat-like character.

The full nature of the invention will be understood from the accompanying drawings and the following description and claims.

In the drawings, Fig. 1 is a front elevation of the transmitter. Fig. 2 is a central vertical section through the same. Fig. 3 is an elevation of a portion of the chambered rubber frame for holding the granular carbon. Fig. 4 is a reproduction of a portion of what appears in Fig. 2 on a larger scale, showing the parts in normal position. Fig. 5 is the same showing the diaphragm member vibrated by a sound wave, the extent of vibration shown, however, being exaggerated for the sake of clearness. Fig. 6 is a section of part of one of the wire frames, and Fig. 7 is an elevation thereof.

There is shown in the drawings herein, for the purpose of illustrating the nature of the invention, a microphone or transmitter suitable for, and adapted to be mounted on, an ordinary telephone stand or otherwise.

It is shown herein, however, somewhat en-

larged for the sake of clearness, and it should be preferably a little larger than the ordinary telephone transmitter, and of the same shape and without any mouthpiece, as it appears in Fig. 1.

A circular metal casing 10, of the same shape as found in the ordinary telephone transmitter may here be employed and through its rear central portion the usual telephone wires or conductors 11 and 12 extend. Within said casing 10 there is a thick fiber disk 13 mounted by screws 14. It is cup-shaped with the central front portion recessed to receive the members or parts of the device which will hereafter be enumerated and these parts are held in the casing 10 by a retaining ring 15, made preferably of hard rubber, and secured to the fiber disk 13 by screws 16.

Within the cup-shaped disk 13 there is a carbon plate 17 and in front of it a reticulated or perforated rubber frame 18 to form pockets in which granular carbon 19 is placed. The carbon plate constitutes the rear electrode and is connected to the conductor 12 by a binding post 20.

In front of the carbon-holding frame 18 there is an insulated wire netting or reticulated frame 21, extending over the entire area of said frame 18. It is formed of cross wires which may be arranged about twelve to the inch each way for ordinary telephone use. It is preferably flattened by being run between a pair of strong compressing rolls so as to make it thinner and have a smooth outer surface for the foil. It is japanned, or otherwise treated, to render it superficially non-conducting.

Against said reticulated back frame 21 a sheet of metal foil 22 is placed or secured. This is the diaphragm member in the device, but it is very thin and flexible, and preferably non-elastic. It is preferably gold or gold plated foil, but other metallic foil may be used. The foil is held in place against the reticulated back frame 21 by a wire netting or reticulated frame 23 which is placed against the foil so that the latter is held tightly in place between said nettings 21 and 23. It is preferably formed of the same size of wire as the netting frame 21, but preferably of copper wire or other good electrical conductor, and it is also preferably rolled flat for the reason above specified. This conducting wire frame 23 is a part of the front electrode and in front of and against it there is a conducting ring 25 that extends all the way around and to it there is connected a copper strip 26 that runs through an opening in the disk 13 and back to a binding post 27 for the wire 11.

In front of what may be called the diaphragm construction, made of the foil and the two wire frames 21 and 23, there is placed a relatively thick mat or layer 28 of

wool-like material and it is retained by another wire frame 29 in front of it which is held in place by the retaining ring 15 and so it will compress the wool-like material 28 and cause it to yieldingly hold the conducting wire frame 23 against the foil 22 and hold the foil securely against the rear wire frame 21 and hold said frame 21 against the carbon holding frame 18.

10 The wool-like material 28 is preferably composed of steel wool, but it may be made of other wool or wool-like material. However, it is preferable and believed to be necessary to the successful operation of the device that this wool-like material be substantially resilient, elastic and so that it will retain its position normally and be penetrable by the sound waves and yet not respond to them. While a front reticulated frame is 20 preferable, still the apparatus works reasonably well without such front reticulated frame, particularly if the wool-like material is moderately pressed against the diaphragm member. Also the apparatus operates well if the rear reticulated frame is not insulated, as some of the current still goes through the diaphragm to the carbon as heretofore described.

The foregoing description and the associated drawings explain substantially the general features and construction of this invention, although it is not limited to many of the particular details therein set forth. It is evident from what has been said that 30 the gold foil or what may be termed the diaphragm will not vibrate as a whole and is so mounted and held that it is divided into a large number of relatively small diaphragm sections located substantially in the same plane. Each of these sectional portions of the foil is capable of vibration under the influence of the sound waves, as indicated by the arrow in Fig. 4, and regardless of the other sections of the diaphragm. 40

45 These sectional diaphragms are, therefore, very small and the foil very thin and pliable so that it is vibrated by a very slight sound wave which renders it extremely sensitive. While a considerable bend is shown 50 in the diaphragm in Fig. 5, that is an exaggeration, as the movement of the small sectional diaphragm is very slight, entirely too slight to be illustrated to scale in the drawings. Several small sectional diaphragms as explained are in engagement 55 with the carbon granules in one compartment so that they engage the same body of carbon granules. Therefore each sectional diaphragm does not have a body of carbon 60 granules for itself alone. Very slight movements of the diaphragm cause it to engage some of the granular carbon and cause the same to operate in the usual manner in microphones.

65 By providing the transmitter with such similar and sensitive diaphragm sections, it is enabled to be influenced by relatively slight sound waves and to transmit and reproduce the same, and since there is a large number of sectional diaphragms and they 70 are substantially the same in size and character, their effect in reproducing the sound is cumulative. That is, they act in the same way and at the same time and being distributed over a relatively considerable 75 area, they more accurately reproduce the tones, especially those of the human voice and give to the reproduced tones the timbre and quality of the human voice; and since the minor tones are reproduced, the major 80 tones are thereby relatively subordinated so that they are not so greatly emphasized as to cause a mere noise. In fact, it is the minor tones that enable different tones or sounds to be distinguished and the loud 85 major tones that cause the confusion of sounds in the ordinary telephone and which render it difficult to distinguish the tones or sounds. Therefore, one of the important results of this transmitter is the purity of tone 90 it causes to be reproduced.

One result, it is believed, of the large number of very small sectional diaphragms of similar character and action is the amplification by them of the very minor tones, where 95 by in the reproduced tones or sounds, they have the same relative strength or character that the major and stronger minor tones have in the original tones or sound. This amplification not only results from the multiplicity of the sectional diaphragms, but from the free and sensitive movement of each small diaphragm because of the character of the diaphragm material. This result is impossible where the diaphragm is made of a sheet of material that must be vibrated wholly or almost wholly and where there is much inertia and lag. The sensitiveness of the diaphragm in this invention prevents 100 lag in the minor tones so that in the reproduced tones or sounds, the minor tones have the original position relative to the major tones in point of time as well as in strength. 105

Because of the sensitiveness of this instrument, it is unnecessary to have a mouthpiece or to be near the instrument and in practical use it does not have to be handled, but can be talked into from any part of the room and with ordinary tone of voice and when one's 110 back is turned to it.

The nature and construction of this instrument enables it to be made of any size that may be required and desired for any use or situation. The ordinary transmitter cannot be made large because the diaphragm 115 would become too heavy and the inertia thereof too great to be vibrated by the ordinary sound waves. Since, however, in this instrument the small sections of the foil constitute a multiplicity of diaphragms and they 120

125

130

are substantially alike and the sheet of foil as a whole does not vibrate, the action is the same whether there would be a small or large number of diaphragm sections. Hence, the 5 instrument can be three feet in diameter as well as three inches. The effect of enlargement is to increase the power of the instrument and adapt it for use in conventions and for reproducing distant and delicate tones 10 and particularly in connection with radio telephoning and the like.

Another characteristic is that a very great 15 energizing current may be used in connection with the instrument without the hissing and 18 sizzling noise heretofore associated with the use of large currents. This is not only of value in ordinary local telephoning, but particularly in long distance work and in radio telephony and the like.

20 By "carbon holder" is meant herein a holder for carbon granules.

The diaphragms in broadcasting radio devices are said to be stretched so taut that they are capable of vibrating with a greater 25 frequency than the air waves that would come to it. In this invention, such high frequency is due to the smallness of the diaphragm or diaphragm section which enables it to vibrate at a greater frequency than the 30 air waves that come to it. But in order to practically utilize such small diaphragm there must be a multiplicity of them in a transmitter acting independently and synchronously and as a unit. Hence the smallness 35 of the diaphragm sections provides for the desired frequency of vibration and also renders them synchronous for if the diaphragm sections were large they would not act with perfect synchronism, especially for 40 the air waves which are relatively weak and of high frequency.

The invention claimed is:

1. A microphone for telephonic instruments, including a multiplicity of independently and synchronously acting diaphragms 45 located substantially in the same plane, and means for holding said diaphragms in engagement with a body of carbon granules.

2. A microphone for telephonic instruments, including a multiplicity of independently and synchronously acting diaphragms located substantially in the same plane, stationary means for engaging the margins of 55 said diaphragms, and a body of carbon granules for engagement by said diaphragms.

3. A microphone for telephonic instruments, including a plurality of similar diaphragm sections formed of relatively thin pliable metal sheet and located substantially 60 in the same plane, stationary backing carrying the same, and a body of carbon granules in engagement with said diaphragm sections.

4. A microphone for telephonic instruments, including a multiplicity of diaphragms 65 connected collectively in parallel

capable of vibration independently of each other, stationary means for mounting the same which engages the margins of said diaphragms, and a body of carbon granules engaging the multiplicity of diaphragms. 70

5. A microphone for telephonic instruments, including a multiplicity of independently and synchronously acting diaphragms in parallel, a stationary frame which engages and holds the margins of said diaphragms, and a body of carbon granules in engagement with said diaphragms. 75

6. A microphone for telephonic instruments, including a diaphragm member formed of a relatively thin pliable metal sheet, means for holding it so as to sectionalize it into a plurality of independently and synchronously acting diaphragm sections, the same body of carbon granules being in engagement with a number of said diaphragm sections. 80

7. A microphone for telephonic instruments, including a thin pliable metal sheet as the diaphragm member thereof, reticulated frames between and by which the diaphragm member is secured so as to sectionalize it into a plurality of independently vibratory and synchronously acting diaphragms. 90

8. A microphone for telephonic instruments, as set forth in claim 7, with means for clamping together the margins of said diaphragm and reticulated frames, for the purpose stated. 95

9. A microphone for telephonic instruments as set forth in claim 7, and a carbon holder adjacent said diaphragm and one of the reticulated frames and provided with a plurality of chambers and granular carbon in said chambers, substantially as set forth. 100

10. A microphone for telephonic instruments including a thin pliable metal sheet as the diaphragm member thereof, a rear reticulated frame against which the diaphragm member is placed, a front reticulated frame for holding said diaphragm member against said rear frame so as to sectionalize the diaphragm member into a plurality of independently vibratory members, and a layer of wool-like material pressing against 110 said front reticulated frame.

11. A transmitter for telephonic instruments, including a thin pliable metal sheet as the diaphragm member thereof, a rear reticulated frame against which the diaphragm member is placed, a front reticulated frame for holding said diaphragm member against said rear frame so as to sectionalize the diaphragm member into a plurality of independently vibratory members, and a layer of metal wool pressed against 120 said front frame.

12. A transmitter for telephonic instruments including a thin pliable metal sheet as the diaphragm member thereof, a rear re- 125

- ticulated frame against which the diaphragm member is placed, a front reticulated frame for holding said diaphragm member against said rear frame so as to sectionalize 5 the diaphragm member into a plurality of independently vibratory members, a layer of wool-like material placed against said front frame, and a reticulated frame in front of said wool-like material for pressing it 10 against said parts to the rear thereof.
13. A microphone for telephonic instruments, including a carbon holder provided with a plurality of chambers, carbon granules in said chambers, a thin pliable metallic sheet as the diaphragm member, and means for holding said sheet in contact with the carbon granules in the chambers of the carbon holders and which sectionalizes said diaphragm sheet into a plurality of independently vibratory diaphragms in front of each carbon holding chamber.
14. A microphone for telephonic instruments including a carbon holder providing a plurality of chambers, granular carbon in said chambers, a reticulated frame coated with insulating material adjacent to said carbon holding frame, a relatively thin flexible, non-elastic metallic sheet as the diaphragm member adapted to contact with 20 said insulated reticulated frame and the granular carbon, and a reticulated frame made of conducting material placed against and engaging the front side of said diaphragm member.
15. A microphone for telephonic instruments including a rear fiber disk, a carbon holder in front thereof providing a plurality of chambers, granular carbon in said chambers, a reticulated frame adjacent to 25 said carbon holder and coated with non-conducting material, a relatively thin pliable metallic sheet as the diaphragm member placed against said coated frame, a reticulated frame made of conducting material in front of and adjacent to said diaphragm member, a layer of yielding material adjacent to said conducting frame, a marginal front ring, and means for securing it to said rear disk so as to compress and hold the 30 margins of said carbon holder, frames, diaphragm member and yielding layer together.
16. A microphone for telephonic instruments including a cup-shaped rear fiber disk, a carbon holder in front thereof providing a number of chambers, granular carbon in said chambers, a reticulated frame adjacent to said carbon holder and coated with non-conducting material, a relatively thin pliable metallic sheet as the diaphragm member 35 placed against said coated frame, and a reticulated frame made of conducting material in front of and adjacent to said diaphragm member, a layer of yielding material adjacent to said conducting frame, a marginal front ring, a reticulated frame in front of 40 said layer of yielding material, a ring engaging the margin of said last mentioned frame, and means for securing said ring to said cup-shaped rear disk so as to compress and hold together the margins of said carbon holder, frames, diaphragm member and layer of yielding material.
17. In a microphone for telephonic instruments, the combination of a carbon electrode, a stationary and reticulated metal frame in front of said carbon electrode, said frame being insulated on the side thereof facing the carbon electrode, a diaphragm member adjacent the front side of said frame, granular carbon between the carbon electrode and said frame and diaphragm, and means for holding the diaphragm member against said frame so that the sections of the diaphragm member covering the openings in said frame will be independently vibratory, substantially as set forth.
18. In a microphone for telephonic instruments, the combination of a carbon electrode, a stationary and reticulated metal frame in front of said carbon electrode, said frame being insulated on the side thereof facing the carbon electrode, a diaphragm member adjacent the front side of said frame, granular carbon between the carbon electrode and said frame and diaphragm, and a conducting ring for holding the margin of said diaphragm member tightly against said frame.
19. In a microphone for telephonic instruments, the combination of a carbon electrode, a stationary and reticulated metal frame in front of said carbon electrode, said frame being insulated on the side thereof facing the carbon electrode, a diaphragm member adjacent the front side of said frame, granular carbon between the carbon electrode and said frame and diaphragm, a conducting ring for holding the margin of said diaphragm member tightly against said frame, and yielding means in front of the diaphragm for yieldingly holding it against said metal frame and permitting the sections thereof covering the opening in said frame to be independently vibratory.
20. In a microphone for telephonic instruments, the combination of a carbon electrode, a stationary and reticulated metal frame in front of said carbon electrode, said frame being insulated on the side thereof facing the carbon electrode, a diaphragm member adjacent the front side of said frame, granular carbon between the carbon electrode and said frame and diaphragm, a conducting ring for holding the margin of said diaphragm member tightly against said frame, another reticulated frame in front of said diaphragm member and marginal conducting ring, metal wool in front of said front metal frame and engaging it and the diaphragm member, and means for securing 115 120 125 130

all of said elements tightly together at their margin.

21. A microphone for telephonic instruments, including a thin pliable metal sheet as the diaphragm member thereof, a rear reticulated frame against which the diaphragm member is placed, a layer of wool-like material in front of said diaphragm,

and means for pressing the wool-like material against the diaphragm member so as to sectionalize it into a plurality of independently vibratory members. 10

In witness whereof, I have hereunto affixed my signature.

DUDLEY HOWARD WIGGINS.
